Application May 4, 1932, Serial No. 609,059

8 Claims. (Cl. 20—8)

There has recently been developed a floor in which boards are laid edge to edge upon trough-like supporting strips; being held down by clips that are interlocked with the strips, extend up into the joints between the boards and are interlocked at their upper ends with the boards. The present invention relates to this type of floor construction and has for its object to improve the same.

10 Heretofore the floor boards have had in their long edges grooves placed there solely for the purpose of receiving flanges on the clips; thus requiring boards that differ considerably in construction from the ordinary, highly satisfactory tongue and groove boards. Specifically considered, the present invention may be said to have for its object to make it possible quickly and easily to secure tongued and grooved boards, substantially like those that have long been in use, to an underlying foundation by means of clips entered into the joints between the boards.

15 While the invention is particularly adapted for use in connection with floors, it will, of course, be understood that it may be employed wherever a structure composed of boards laid edge to edge is to be laid upon or against a foundation or wall.

The various features of novelty whereby my invention is characterized will hereinafter be pointed out with particularity in the claims; but, for 20 a full understanding of my invention and of its objects and advantages, reference may be had to the following detailed description taken in connection with the accompanying drawing, wherein:

25 Figure 1 is a vertical section, taken transversely of the floor boards, through a floor embodying my invention, the section being on a plane represented by line 1—1 of Fig. 2; Fig. 2 is a section on line 2—2 of Fig. 1, the tongues and clips being shown in elevation and the end and middle portions of the floor being omitted; Fig. 3 is a section, on a much larger scale than Figs. 1 and 2, on line 3—3 of Fig. 2, only a small fragment being shown; and Figs. 4, 5 and 6 are, respectively, a top plan view, an end view, and a side elevation of one of my improved clips.

30 In the drawing I have illustrated my invention as applied to a floor and, for the sake of brevity, the detailed description will be confined to this particular embodiment, as the principle of the invention is the same whether the boards lie in a horizontal plane, in a vertical plane, or at an angle to the vertical, or whether they lie above or below or beside the support or foundation therefor.

35 Referring to the drawing, 1 represent shallow metal troughs or channels each having the upper marginal portions of its side walls turned inwardly to form horizontal flanges 2. The members 1 are secured to an underlying floor or supporting structure 3. The flooring proper consists of boards 4, 4 laid edge to edge upon the members 1, crosswise of the latter; the members 1 and the supporting structure 3 therefore serving as the foundation for the floor. The floor boards are 40 substantially the same as the ordinary tongued and grooved boards in common use; each board having at one long edge a tongue 5 and at the opposite long edge a groove 6.

45 The boards are held to the foundation and in close contact with each other by means of clips interlocked with the metal channel members for sliding movements along the latter while being held against vertical movements; these clips rising up into the joints between the boards, partly embracing the tongues, and nested in the grooves. Therefore, each clip, through engagement with a tongue on one board, holds the corresponding side of that board down whereas, because it is 50 nested in the groove of the adjacent board, it holds that side of the latter board down. In other words, each board is engaged by two rows of clips, a row at each edge.

55 The details of the clips are best shown in Figs. 4, 5 and 6. Each clip is preferably made of sheet metal properly cut and bent to produce a flat body portion 7 and a trough-like or hooked tongue-engaging portion 8. The lower part 9 of the body portion of the clip is made approximately 55 as wide as the internal width of one of the metal channels. At a distance above the lower edge of the clip equal to the vertical interior depth of one of the metal channels, beneath the flanges on the latter, are two notches 10, 10 cut inwardly from the side edges; the distance between the inner ends of the two notches being somewhat less than the distance between the inner edges of the two flanges on one of the metal supporting strips. Therefore, the clip may be entered through the end of one of the metal supporting strips, or through the top, the sections 9 underlying the flanges which, in turn, are received in the notches 10. The flat portion 11 above the notches has a vertical height approximately equal 60 to the shortest distance from the plane of the under face of one of the floor boards to the tongue on that board. The hook-shaped part 8 on the clip projects laterally from what may be termed the upper long edge of the part 11, and is shaped 65

to lie against the under side of a tongue on one of the floor boards, over the edge of the tongue, and partly across the top. What may be termed the shank portion of the hook is slightly shorter than the width of the tongue on the board measured transversely of the length of the board, so that the part 11 of the clip does not touch the corresponding section 12 of the edge face on the board just below the tongue with which the clip is engaged. In other words, the body portion of the board does not interfere with the clip in the process of forcing the hook portion thereof tightly upon the tongue. Furthermore, the hook portion of the clip is so shaped that, when it is pressed tightly upon the tongue, it bites into the upper face of the latter and thus serves to draw the board tightly against the underlying foundation. Although the free end of the hook is shown as extending a short distance inwardly over the top of the tongue, the biting of the free end of the hook into the tongue leaves the latter free from upward projections on the upper side; and therefore the clips do not interfere with the normal surface contact between the tongue and the overlying portion of the adjacent board, but this contact is effective throughout the entire length and width of the tongue.

While the edge face 12 of the board is set back so as not to engage with the clip, the corresponding edge face 13, on the opposite side of the board, is advanced far enough to engage the part 11, namely, the upper portion of the flat section of the clip, at the time that the hook portion of the clip is seated in the groove just above the edge face 13. Furthermore, the edge face 13 is preferably inclined downwardly and outwardly from the groove of the board to the bottom face of the board so that, when the floor has been laid, the flat body portions of the clips are canted somewhat, as best shown in Fig. 3, so as to cause sharp edges on the part 9 to be pressed against the under sides of the flanges on the metal supporting pieces, while sharp edges on the parts 11 are caused to be pressed against the top faces of the flanges. In other words, the clips are locked to the foundation so as to leave not the slightest looseness which would permit the boards to move up and down ever so slightly.

In laying the floor, the metal supports are first secured to the supporting structure. The first board is laid crosswise of the metal supports and then clips are inserted and moved along the troughs or channels until they are engaged with the tongue on the board. The next board is then laid on the supports and driven toward the first board until the joint between the two boards is closed, as viewed from above. This second board, in its movement toward the first board, comes first into engagement with the row of clips, carrying these clips with it until the clips are firmly driven home over the tongues. Other boards are then laid, one after another, until the floor is completed.

It will thus be seen that I am able to secure boards having tongues and grooves, substantially like those in common use, by means of clips which are strong and rugged which properly position themselves by the mere act of engaging them with the supporting foundation, and which are then effectively interlocked, each with two boards at a time, by the mere relative movements of the floor boards and without requiring any attention to be paid by the workman to the clips themselves. Therefore, it is possible not only to lay a wooden floor where this has not

heretofore been practicable, but a floor may actually be laid in less time than is required for an ordinary nailed floor.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In a floor, a foundation, boards laid edge to edge on said foundation and joined by tongues and grooves, clips rising from the foundation and interlocked therewith for sliding movements at right angles to said tongues and grooves and against vertical movements, each clip having a hook part at the upper end embracing the edge of and biting into the top of one of said tongues and nested in the groove in which that tongue is engaged, and the effective length of each clip from the upper face of said foundation to the clip of the hook being such that, when the hook is forced upon the edge of a tongue, the tip of the hook is compelled to sink into the tongue after the board has been firmly seated on the foundation.

2. In a floor, a foundation, a tongued and grooved board resting on said foundation, a clip anchored to the foundation against vertical movements while free to move at right angles to the long edge of said board, said clip having at the upper end a part shaped to embrace the outer portion only of the tongue and bite into the top thereof and exert a downward pull on the tongue when forced upon the tongue, and said tongue-engaging part on the clip being adapted to nest in the groove of a second board which receives the tongue on the first board.

3. In a floor, parallel trough-shaped foundation members having inwardly turned flanges at the upper long edges of their side walls, tongued and grooved boards resting on and crosswise of said foundation members, clips rising from the foundation members and each having in opposite edges notches to receive the flanges of the corresponding foundation member and lock the clip against vertical movement while permitting it to slide lengthwise of its foundation member, each clip extending into the joint between two of the boards and fitting over the tongue and nested in the groove forming part of that joint, and each board being widened on the grooved side whereby the clips are caused to be canted and locked tightly to the foundation members when the boards are forced into close contact with each other.

4. In a floor, parallel trough-shaped foundation members having inwardly turned flanges at the upper long edges of their side walls, tongued and grooved boards resting on and crosswise of said foundation members, clips rising from the foundation members and each having in opposite edges notches to receive the flanges of the corresponding foundation member and lock the clip against vertical movement while permitting it to slide lengthwise of its foundation member, each clip extending into the joint between two of the boards and nested in the lower portion of the groove forming a part of that joint, the upper free end of each clip being interlocked with the adjacent tongue so that a downward pull on the clip exerts a downward pull on the tongue, and each board being narrowed on

the tongue side below the tongue whereby clips are caused to be canted and locked tightly to the foundation members when the boards are forced into close contact with each other.

5. In a floor, parallel trough-shaped foundation members having inwardly turned flanges at the upper long edges of their side walls, tongued and grooved boards resting on and crosswise of said foundation members, clips rising from the 10 foundation members and each having in opposite edges notches to receive the flanges of the corresponding foundation member and lock the clip against vertical movement while permitting it to slide lengthwise of its foundation member, each 15 clip extending into the joint between two of the boards and into the groove and into interlocking relation with the tongue forming that joint, the meeting edges of the boards below the tongues and grooves being shaped to permit the clips to 20 be canted and locked tightly to the foundation members when the boards are forced into close contact with each other.
6. In a floor, the combination of a supporting channel the legs of which have upper inwardly-directed flanges, a plurality of floor boards resting crosswise on the channel, a plurality of clips for securing the floor boards to the channel, each clip having an upper portion extending between adjacent floor boards and engaging therewith to 25 hold them down on the channel, and a lower portion interlocked with the channel and having notches receiving said flanges, and means for canting the clips from the vertical, as the floor boards are forced into engagement, to cause said 30 clips to bind upon the flanges of the channel and

thus prevent displacement lengthwise of the channel.

7. In a floor, the combination of a supporting channel the legs of which have upper inwardly-directed flanges, a plurality of floor boards resting crosswise on the channel, a plurality of clips for securing the floor boards to the channel, each clip having an upper portion extending between adjacent floor boards and engaging therewith to hold them down on the channel, and a lower portion interlocked with the channel and having notches receiving said flanges, and means for canting said clips from the vertical, as the floor boards are forced into engagement, to cause the walls of said notches to bind on said flanges and 15 thus prevent displacement of the clips lengthwise of the channel.

8. In a floor, the combination of a supporting channel the legs of which have upper inwardly-directed flanges, a plurality of floor boards resting crosswise on the channel and having tongues and grooves interengaging to interlock the boards, a plurality of clips for securing the floor boards to the channel, each clip having an upper hook-like portion engaging a tongue and seated 20 in the corresponding groove to hold the boards down on the channel, and a lower portion interlocked with the channel and having notches receiving said flanges, and means for canting the 25 clips from the vertical, as the floor boards are forced into tongue and groove engagement, to cause the walls of said notches to bind on said flanges and thus prevent displacement of the clips lengthwise of the channel.

OSCAR L. JOHNSON. 35
